UNITED STATES PATENT OFFICE.

VICTOR EMILIUSS HANSEN, OF BROOKLYN, NEW YORK, ASSIGNOR TO INTERNATIONAL CIGAR MACHINERY COMPANY, OF NEW YORK, N. Y., A CORPORATION OF NEW JERSEY.

NICKING DEVICE FOR CIGAR-WRAPPING MACHINES.

1,188,542.

Specification of Letters Patent. Patented June 27, 1916.

Application filed May 3, 1915. Serial No. 25,382.

To all whom it may concern:

Be it known that I, VICTOR EMILIUSS HANSEN, a citizen of the United States, residing at Brooklyn, county of Kings, and State of New York, have invented a new and useful Improvement in Nicking Devices for Cigar-Wrapping Machines, of which the following is a specification.

This invention relates to an improvement 10 in nicking mechanism for cigar wrapping machines, and is particularly adapted for use in connection with automatic cigar making machines.

In cigar wrapping machines, it is necessary that the wrapper be nicked at the time 15 the flag end of the wrapper is wound about the head of the cigar. Various mechanisms have heretofore been used for this purpose but they were all more or less complicated 20 and troublesome.

The main object of the present invention is the production of a nicking device for cigar machines extremely simple in construction and more efficient in operation.

25 A further object of the invention is the production of a cigar wrapping device having a tension plate one end of which is downwardly curved adjacent the head of a cigar in the wrapping device, this downwardly 30 curved end being slotted so that a rotary nicking device having widely separated nicking knives can operate at high speed through said slot at the head of the cigar in order 35 to nick the wrapper as it is drawn down over the curved end of the tension plate.

With these and other objects not specifically mentioned in view, the invention consists in certain constructions and combinations which will be hereinafter fully 40 described and then specifically set forth in the claims hereunto appended.

In the accompanying drawings, which form a part of this specification and in which like characters of reference indicate 45 the same or like parts, Figure 1 is a front elevation of a device constructed in accordance with the invention. Fig. 2 is a side elevation of the structure shown in Fig. 1. Fig. 3 is a fragmentary plane view of a part 50 of the structure shown in Figs. 1 and 2. And Figs. 4 and 5 are detail views of the rotary nicking cutter shown in the other figures.

In carrying the invention into effect, there

is provided means for rotating a cigar bunch 55 and delivering a wrapper thereto, and a wrapper nicking device comprising a plurality of widely separated nicking knives, and means for successively moving said knives at high speed past the head of a cigar 60 lying within the bunch rotating means and into the path of the flag of the wrapper as it is wound about the bunch. In the best constructions, the widely separated nicking knives are mounted upon, or formed upon, a 65 disk rotating at high speed, and there is further provided a tension plate having a curved end over which the wrapper is drawn as it is wound about the cigar head, this 70 curved head being provided with a slot through which the nicking knives work. The above elements may be varied in construction within wide limits.

The device selected to illustrate the invention is but one of many possible concrete 75 embodiments of the same, and the invention therefore is not to be restricted to the precise details of the structure shown and described.

Referring to the drawings, 6 indicates the 80 main roll and 7 indicates the coöperating rolls of a group of rolls forming means for rotating a cigar bunch. There is further provided a suction wrapper support marked 8, the function of which is to support and deliver a wrapper to a cigar bunch 85 lying within the group of rolls 6—7. The particular construction of the rolls 6 and 7, and of the wrapper support 8, is well known in the art and further description 90 thereof is unnecessary to a complete understanding of the invention. Such further description is therefore omitted herefrom in the interest of brevity. The rolls 6 and 7 are suitably supported in a casting 9, and 95 to this casting is secured a shear plate 10 at the point where lies the head of a cigar within the group of rolls 6—7, and is clearly shown in Fig. 1. Coöperating with this shear plate is a disk 11 having a plurality of nicking knives 12 formed thereon or affixed thereto. The disk 11 is fast upon a shaft 13 suitably journaled in bearings formed in a bracket 14, which bracket is pivoted at 15 to a second bracket 16, this 100 second bracket being secured to the main frame 17 of the machine. Threaded 105 through the bracket 14 are two screws 18

and 19, the screw 18 bearing against the main frame 17 and the screw 19 bearing against the bracket 16. By means of these screws, the bracket 14, and of course the shaft 13 and disk 11, may be adjusted in a direction transverse to the axis of a cigar bunch lying within the group of wrapper rolls. Upon the outer end of the shaft 13 is fixed a pulley 20, over which runs a belt 21 deriving its motion from a large pulley 22 fixed upon a shaft 23 which is one of the main shafts of the machine. The shaft 13 and the disk 11 rotate at high speed, and the nicking knives 12 are widely separated 15 on the periphery of the disk 11 partly because the speed of the nicking knives is greatly in excess of the speed of the wrapper being wound about the cigar head, and partly to prevent displacement of the 20 flag of the wrapper during the head winding operation that would occur if the nicking knives were near enough to produce a fan-like action that would lift the wrapper flag from its normal position and thereby 25 prevent proper nicking. A belt tightening pulley 24 is provided for the belt 21 and is carried upon an arm 25 suitably clamped upon the pivot 15 before referred to.

Coöperating with the bunch rolling 30 means and wrapper delivering means is a tension plate 26 having one end; that is, the end adjacent the head of the cigar, curved downwardly at 27, this curved end being provided with a slot 28 through 35 which the nicking knives 12 can operate. The purpose of the curved end 27 of the tension plate is to provide a suitable support for the flag of the wrapper as it is wound about the cigar head and after it 40 leaves the wrapper support 8. The wrapper flag carries a small quantity of paste upon its under surface, applied thereto in any one of the various ways known in the art, and this pasted surface dragging down over 45 the curved end 27 of the tension plate tends to keep the flag properly stretched as it moves downwardly over said curved end. Furthermore, it tends to hold the flag of the wrapper against displacement as the 50 nicking knives 12 move through the slot 28 and coöperate with the shear plate 10 to nick the wrapper at the cigar head. Apart from this curved end, the tension plate 26 is of a type well known in the art and is 55 moved in and out of operative position by means of a lever 29 fulcrumed at 30 and controlled by a cam 31 in a manner well known in the art. The tension plate is raised and lowered by means of an adjustable connecting rod 32 and a bell-crank lever 33 controlled by a cam 34 in a manner well known in the art. Since the particular construction of this tension plate controlling mechanism is well known in the art, 60 and since further description thereof is un-

necessary to a full understanding of the invention, such further description is omitted herefrom in the interest of brevity.

What is claimed is:

1. In a cigar wrapping machine, the combination with means for rotating a cigar bunch and delivering a wrapper thereto, of a wrapper nicking device permanently located in juxtaposition with the head end of the bunch rotating means and comprising a plurality of widely separated nicking knives, and means for successively moving said knives at high speed past the head of a cigar lying within the bunch rotating means and into the path of the flag of the wrapper as it is wound about the bunch. 70

2. In a cigar wrapping machine, the combination with means for rotating a cigar bunch and delivering a wrapper thereto, of a wrapper nicking device permanently located in juxtaposition with the head end of the bunch rotating means and comprising a fixed shear plate and a plurality of widely separated nicking knives, and means for successively moving said knives at high speed past the head of a cigar lying within the bunch rotating means and into the path of the flag of the wrapper as it is wound about the bunch. 85

3. In a cigar wrapping machine, the combination with means for rotating a cigar bunch and delivering a wrapper thereto, of a wrapper nicking device permanently located in juxtaposition with the head end of the bunch rotating means and comprising a circular disk carrying a plurality of widely separated nicking knives, and means for rotating the disk and knives at high speed past the head of a cigar lying within the bunch rotating means and into the path of the flag of the wrapper as it is wound about the bunch. 90

4. In a cigar wrapping machine, the combination with means for rotating a cigar bunch and delivering a wrapper thereto, of a wrapper nicking device permanently located in juxtaposition with the head end of the bunch rotating means and comprising a shaft the axis of which is parallel to the axis of a cigar lying within the rotating means and a circular disk fixed to said shaft and carrying a plurality of widely separated nicking knives, and a belt and operating connections for rotating said shaft to cause said knives to move at high speed past the head of a cigar lying within the bunch rotating means and into the path of the flag of the wrapper as it is wound about the bunch. 110

5. In a cigar wrapping machine, the combination with means for rotating a cigar bunch and delivering a wrapper thereto, of a wrapper nicking device permanently located in juxtaposition with the head end of the bunch rotating means and comprising an 125

- adjustable bracket and a shaft journaled in said bracket and a disk fixed upon said shaft carrying a plurality of widely separated nicking knives, and a belt and operative connections for rotating said shaft to cause said knives to move at a high speed past the head of a cigar lying within the bunch rotating means and into the path of the flag of the wrapper as it is wound about the bunch.
6. In a cigar wrapping machine, the combination with bunch rolling means, of wrapper delivering means, a tension plate for controlling the delivery of a wrapper from the wrapper delivering means to the bunch rolling means said tension plate being downwardly curved at one end and provided with a slot adjacent the head of a cigar lying within the bunch rolling means, and a wrapper nicking device comprising a plurality 15 of widely separated nicking knives, and means for successively moving said knives at high speed through the tension plate slot and past the head of a cigar lying within the bunch rolling means and into the path 20 of the flag of the wrapper as it moves down over the curved end of the tension plate and is wound about the bunch.
7. In a cigar wrapping mechanism, the combination with means for rotating a cigar bunch and delivering a wrapper thereto, of a wrapper nicking device permanently located in juxtaposition with the head end of 25

the bunch rotating means and transversely adjustable with respect to the bunch rotating means and comprising a plurality of 35 widely separated nicking knives, and means for successively moving said knives at high speed past the head of a cigar lying within the bunch rotating means and into the path of the flag of the wrapper as it is wound about the bunch.

8. In a cigar wrapping machine, the combination with means for rotating a cigar bunch and delivering a wrapper thereto, of a wrapper nicking device permanently located in juxtaposition with the head end of the bunch rotating means and comprising a shaft the axis of which is parallel with and below the axis of a cigar lying within the rotating means and a circular disk fixed to 45 said shaft and carrying a plurality of widely separated nicking knives, and means for rotating said shaft to cause said knives to move at high speed past the head of a cigar lying within the bunch rotating means and 50 into the path of the flag of the wrapper as it is wound around the bunch.

In testimony whereof, I have signed my name to this specification in the presence of two subscribing witnesses.

VICTOR EMILIUS HANSEN.
